RESERVOIR TYPE SMOKING PIPE

Wensan Wang, Setagaya-ku, Tokyo, Japan

Application February 24, 1956, Serial No. 40,309

Term of patent 14 years

(Cl. D85—8)

Figure 1 is a side elevational view of a reservoir type smoking pipe, according to the present invention, showing my new design;

Figure 2 is a top view of the pipe of Figure 1;

Figure 3 is a bottom view of the pipe of Figure 1;

Figure 4 is an elevational view of the pipe of Figure 1, taken from the left of the aforesaid figure;

Figure 5 is an elevational view of the pipe of Figure 1 taken from the right of the aforesaid figure.

Portions of the drawing figures are diagonally lined to indicate transparency.

I claim:

The ornamental design for a reservoir type smoking pipe, as shown and described.
